COATING MACHINE

Eugene C. Zablocki, Detroit, Mich., assignor to
 Briggs Manufacturing Company, Detroit,
 Mich., a corporation of Michigan

Application March 23, 1936, Serial No. 70,346

9 Claims. (Cl. 91—37)

This invention relates to coating machines and has for one of its principal objects to provide a machine which will quickly and economically apply a coating of adhesive or other material to flat articles. In particular, one of the important objects of this invention is to provide a means for economically applying adhesive to the backing members of arched trim panels which extend around above the windows of closed automobile bodies, the adhesive serving to secure the trim fabric to the panel or backing member.

Another object of this invention is to provide a coating machine having rotary brushes and a simple means of feeding to the brushes the material to be applied by the machine.

Another object of this invention is to provide a coating machine by means of which a single person can coat articles as fast as several persons using spray guns or other means heretofore utilized.

Other objects of this invention will appear in the following description and appended claims, reference being had to the accompanying drawings forming a part of this specification wherein like reference characters designate corresponding parts in the several views.

Fig. 1 is an isometric projection of one of the embodiments of the invention.

Fig. 2 is a side elevation of the machine shown in Fig. 1.

Fig. 3 is a front elevation with the feeding table or stand seen in Fig. 1 removed and with parts broken away or shown in section.

Fig. 4 is a sectional view on the line 4—4 of Fig. 3 taken in the direction of the arrows.

Fig. 5 is a partial rear elevation.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

As is shown in the figures, the present embodiment of the invention, herein illustrated by way of example, comprises a pair of rotary brushes 10 and 11 mounted one above the other in suitable bearings 12 and 13. The lower bearings 13 are fixed, being secured to the sides of a sheet steel receptacle 14, while the upper bearings 12 are

adjustable, being vertically movable in guides 15 mounted on the ends of an upward extension 14a of the receptacle and adapted to be raised or lowered by screws 16.

The front and rear sides of the receptacle extension 14a are open and the top of the receptacle 14 has an opening 14b (Fig. 4) through which the upper part of the lower brush 11 projects into contact with the bottom of the upper brush 10, so that thin articles fed between the brushes will be brushed on both sides and so that one brush will supply coating liquid to the other. The lower brush is supplied with coating liquid or adhesive by means of an agitator or splasher 17 located in a reservoir 18 within the receptacle 14 below the lower brush 11. The splasher 17 comprises a horizontal shaft which lies just above the normal level of the coating material 18 and which carries a number of radially extending pins or fingers 17b which reach down into the coating material 18 and splash or throw it up onto the lower brush 11.

The liquid 18 in the splasher tank 14 is supplied from a lower tank or reservoir 19 through pipe line 24 by a pump 20 and drains back through a pipe 21. Valves 22 and 23 in the pump line 24 and drain pipe 21 serve to regulate the level of the liquid 18 in the splasher tank 14 and also allow the tank 14 to be drained into the lower tank 19, from which the liquid can be easily removed when the machine is to be stopped for a time. An overflow pipe 25 leading from the splasher tank 14 to the reservoir 19 prevents the liquid 18 from ever rising above a predetermined level.

The agitator or splasher 17 is driven by a belt 26 from a motor 27 and, in turn, drives the rest of the machine. A gear 28 keyed to the shaft of the splasher 17 drives a large gear 29 which rotates freely on the shaft 31 of the lower brush and is integral with a small gear 30 driving the larger of another pair of gears 32 and 33 freely rotatable on the upper brush shaft 34. The small gear 33 of the pair on the upper shaft 34 in turn drives a large gear 35 keyed to the lower shaft, the lower brush 11 being thus driven at a considerably reduced speed. The upper brush 10 is driven from the lower one 11 by a pair of gears 36 and 37 keyed onto the other ends of the brush shafts 10 and 11. The pump 20 is driven by a belt 38 from one end of the splasher shaft 17a.

A feed table 39 is provided on the receiving side of the machine so that a trim panel backing member 40 to be coated with adhesive can be laid on the table and easily slid in between the

brushes 10 and 11. One end of the table rests upon a pair of legs 41 while the other rests upon the top of the splasher tank 14 so that the table can be easily removed to allow access to the lower part of the machine. Longitudinal angle members 39a at the sides of the table provide guides ensuring proper feeding of the work to the coating rolls.

The discharge side of the machine is provided with a chute 42 to receive the coated articles and in which they can accumulate until they are removed by an attendant. In order to ensure that the thin stampings 40, which the machine is intended to coat, are discharged into the chute 42 and do not stick to the brushes, the brushes 10 and 11 are engaged by wire strippers, combs or discharge fingers 43 which project into the brushes and receive the stamping 40 between them, as it emerges from between the brushes 10 and 11, and direct it into the chute 42.

It will be understood that the agitator and splasher shaft 17 is driven at a relatively high speed, which speed is so regulated as to cause the fingers 17b to throw up onto the lower brush the proper amount of cement required to produce the desired coating on the work 40. By proper settings of the valves 22 and 23 to control the level of the liquid within the reservoir 18 the quantity of cement projected by the fingers 17b onto the brush 11 will be controlled thus governing the thickness of the coating applied to the work.

I claim:

1. In a coating machine, a pair of rotary brushes between which the work to be coated is fed, a reservoir for containing coating liquid, said brushes being out of contact with the liquid in the reservoir, and rotary means for projecting liquid from the reservoir onto a brush.

2. In a coating machine, a pair of rotary brushes between which the work to be coated is fed, a reservoir for containing coating liquid, said brushes being out of contact with the liquid in the reservoir, and rotary means having projecting elements dipping into the liquid and adapted to throw off particles thereof onto a brush.

3. In a coating machine, a pair of rotary brushes between which the work to be coated is fed, a reservoir for containing coating liquid, said

brushes being out of contact with the liquid in the reservoir, and rotary means having projecting elements dipping into the liquid and adapted to throw off particles thereof onto a brush, and means for varying the level of liquid in the reservoir.

4. In a coating machine, a pair of revolving applicator rolls between which the work to be coated is fed, a reservoir for containing coating liquid, said rolls being out of contact with the liquid in the reservoir, a rotatable agitator having projecting elements successively dipping into the liquid and adapted to throw off particles thereof onto one of said rolls, and means for rotating the agitator at a greater speed than said rolls.

5. In a coating machine, a rotary brush, means below the brush for containing coating liquid to be applied by the brush, and means to throw the liquid up onto the brush.

6. A coating machine comprising a pair of rotary cylindrical brushes one above and in contact with the other, a coating liquid receptacle below the brushes, and a rotary liquid supplying member having projections arranged to dip into the liquid and throw it up onto the lower brush.

7. A machine as described in claim 6 having means to regulate the level of the liquid in the receptacle.

8. A coating machine comprising a pair of parallel cylindrical brushes rotating in contact with each other so as to feed thin articles between them, means to apply a coating liquid to one of the brushes, and a plurality of pairs of vertically spaced discharge fingers projecting into the space between the brushes from the side towards which the brushes are adapted to feed articles.

9. A coating machine comprising a pair of parallel cylindrical brushes arranged to rotate in contact with each other, means to apply coating material to one of the brushes, and stationary stripping means projecting into the brushes, said means comprising vertically spaced fingers between which work coated by the machine is discharged.

EUGENE C. ZABLOCKI.
